UNITED STATES PATENT OFFICE.

HENRY O. HALL, OF WASHINGTON, DISTRICT OF COLUMBIA.

GROUND ANCHORAGE FOR FENCE OR OTHER POSTS, SURVEYORS' PEGS, &c.

SPECIFICATION forming part of Letters Patent No. 461,753, dated October 20, 1891.

Application filed January 16, 1891. Serial No. 378,003. (No model.)

To all whom it may concern:

Be it known that I, HENRY O. HALL, a citizen of the United States, residing at Washington, in the District of Columbia, have invented certain new and useful Improvements in Ground Anchorage for Fence and other Posts, Surveyors' Pegs, &c.; and I do hereby declare the following to be a full, clear, and exact description of the invention, such as will enable others skilled in the art to which it appertains to make and use the same.

This invention has reference to an improvement in means for anchoring in the ground with rigidity and immovability the bottom ends of fence-posts, hitching-posts, awning, electric-light, and telegraph poles, also surveyors' pegs, tent-poles, tent-pegs, and other forms of posts, poles, or supports which are commonly made stationary by placing their lower ends within holes excavated in the ground, the object of my invention being to enable a post or peg of any kind to be set in the ground quickly and to provide a device for this purpose which will be cheap, serviceable, durable, and having a permanent rigidity and stationary character of such great excellence that it will be next to impossible to displace or remove it from its position after it has once been fixed; and the invention consists in the construction, arrangement, and combination of parts, substantially as will be hereinafter described and claimed.

In the annexed drawings, illustrating my invention, Figure 1 is a vertical section of one form of my improved anchoring device for poles or pegs of all kinds, said form being the most common and adapted for use with any kind of a fence-post or other pole, it being shown in this figure as set in the ground, one of its grappling-pins being in position in the earth and the other shown as about being placed in position. Fig. 2 is a cross-section of the same, showing all the grappling-pins in position. Fig. 3 is a perspective view of a slightly-modified form of the device particularly adapted for use as a surveyor's peg. Fig. 4 is a perspective view of another form of the surveyor's peg, having four sides, instead of being round, like the kind shown in Fig. 3. Fig. 5 is a vertical sectional elevational view of a still further modified form of fence-post, it being integral with

the pointed anchoring part, which in this case is made solid, instead of hollow, as is the case in Fig. 1, and is provided with curved passages for the passage therethrough of the grappling pins or fingers. Fig. 6 is an elevation of the fence-post with a portion of a wire fence connected thereto, said post being supported by my anchoring device, which is represented in Fig. 1. Fig. 7 is a form of the device similar to that shown in Fig. 5, the pointed anchoring part being solid and the post formed integral therewith, there being certain differences in the shape and arrangement of the post and the pin-passages in the anchoring part. Fig. 8 is a perspective view of a modified form of a hollow peg or point, it having a looped, ribbed, or scalloped form. Fig. 9 is a perspective view of a part of the post which is adapted to enter the form of hollow peg shown in Fig. 8, said post being suitably shaped to conform to the peculiar shape of the said hollow device. Fig. 10 is a perspective view of a form of the device similar to that shown in Fig. 7, with the solid pointed part having four sides, instead of being conical, as in Fig. 7, there being a modification in the arrangement of the passages in the said peg part and a portion of fence being shown arranged in connection with the fence-post proper.

Similar letters of reference designate corresponding parts throughout all the different figures of the drawings.

In Figs. 1 and 2 I have shown the customary and more common form of my anchorage device, it being also represented in operative position in connection with a post and fence in Fig. 6. This general form consists of a hollow conical peg, box, or drive-bar A, having preferably a slightly-elongated point A', which is adapted to enter the earth easily and thus be fixed in position without much labor. This hollow contrivance is designed to be driven into the earth with a few blows of a mallet or other device and caused to be almost completely embedded, its upper end projecting only a very slight distance above the earth's surface. It can be made out of any suitable kind of metal and of any convenient length and diameter. The purpose of this device is to afford a solid and immovable part, to which the fence-post or other

similar pole can be connected quickly and surely and held there permanently. At a suitable point between the tip A' and the upper end of the hollow device A its wall is provided with several perforations a^2 —say three—although there may be, of course, any number which seems most convenient. a a designate grappling pins or fingers made of iron or other metal firm, strong, and unyielding, having sharp points and preferably provided with heads. These pins or fingers are adapted to be inserted loosely within the hollow part A, with their points projecting through the perforations a^2 in the manner shown in Fig. 1, and then be driven down by a suitable plug inserted against them, and thus caused to pass out their whole length through the said holes a^2 , and thus to occupy the position shown in Fig. 1, where one of them is seen firmly embedded through its entire length in the solid ground or earth. When three or several of these firm metallic pins have thus been embedded in the ground, it will be clearly seen and understood that an exceedingly strong and unyielding connection will be made between the earth and the hollow part A. Not only will the hollow part A be fixed immovably by reason of its having been driven into the solid earth without any excavation being made, but this immovability will be supplemented and greatly augmented by the strong and firm connection in the earth of the grappling-fingers a . When these pins or fingers a have been fixed in place, the fence-post, either for city or country fences, a telegraph-pole, a hitching-post, in fact an upright of any kind and for any purpose, may have its lower end inserted into the open upper end of the hollow point A and be firmly connected thereto. In Fig. 6, E represents a post thus connected to the device A. A cap a' may be inserted into the upper end of the peg when so desired.

In Figs. 1, 2, and 6 the hollow peg A is shown as having a round form; but its form is immaterial. It may be round, square, or any other shape, as is preferred. Sometimes when the round form is used small saplings, cut into suitable lengths and driven into the post-point and bolted therein, will form a permanent, substantial, and secure support for any ordinary farm-fence. Where lumber is cheap and plentiful, a square post-point may be used to advantage and scantlings adopted for the post proper to be connected to the post-point. For lawn-fences in cities the post-point of this kind will be especially valuable. A fence of this kind being slight and not heavy or cumbersome, a square or round point with a slender iron post cast integral therewith, if preferred, will be found a very desirable kind of fence-post, for they can be driven and anchored on the lawns and parking without disturbing the grass plats or disfiguring the lawn with loose earth thrown up from unsightly post-holes, and when once planted in the solid soil they will remain per-

fectly fixed and rigid, capable of supporting any kind of fence-post which may be needed. Of course the iron post may be made separate from the post-point and then soldered thereto in the same manner as is now done when granite or iron blocks are used for the foundations of posts. There is a very wide diversity of forms of post that may be used in connection with the post-point A and its equivalent modified variations. It is unnecessary to enumerate them here. A simple allusion will be sufficient, for it will be clearly evident that these post-points can be used for awning-posts, hitching-posts, electric-light posts, and even telegraph-poles, and will be found especially valuable in paved cities, as they can be driven down without disturbing more than a few square inches of pavement, sufficient only to allow them to be driven into the ground where they are securely anchored underneath the solid undisturbed pavement. They can be driven into the ground to any desired depth, and then by placing the grappling-pins in position great strength in the anchorage is secured.

Having thus described the leading and general form of the post-point or hollow box or drive-bar, I will now proceed to describe only the slightly-different forms, which are all the equivalents of the first, and are simply given by way of illustration in order to exhibit more clearly how the leading features of the invention can be carried into practical effect in slightly-differing constructions.

In Fig. 5 we have a fence-post D' cast integral with a conical post-point D, which post-point, instead of being hollow, like the post point or peg A, is made solid throughout, with the exception of a few (three or more) passages d , which are designed to receive pins or grappling-points similar to the pins a , (shown in Figs. 1 and 2,) differently shaped to suit the passages in which they lie. These passages d run from the top of the post-point D to a suitable place about midway of the point D, where they allow the pin d' or d^2 , as the case may be, to emerge from the post and enter the earth, taking the position shown in dotted lines in Fig. 5. Pin d' is shorter than pin d^2 . Pin d^2 is made long enough, so that its head will remain at the top of the post-point, while about half of it, say, is embedded in the earth. Referring now to Fig. 7, we will see that it has a construction somewhat similar to that shown in Fig. 5. The post F', however, is square, instead of round, like post D'. The post F' is cast integral with the conical post-point F, which point is provided with curved openings, which run from the top of the post-point F to a suitable point about midway of the height of said point F. These passages f are, however, curved differently from the passages d , although the difference is not material, and the passages are all equivalents of each other.

Referring to Fig. 10, we find a structure quite similar to Fig. 7. The post G' in Fig.

10 is similar to the post F' in Fig. 7 and is made integral with the four-sided post-point G, which is provided with passages g. These passages g run from the upper end of the 5 post-point G and pursue a vertical course directly downward for some little distance, and then curving quickly at g' they run to the opposite side of the post-point G. These passages g' are adapted to receive pins made 10 of strong wire or metal of some kind, and the idea is to have these pins driven into the passages with a few firm strong blows, which will cause the pins to be bent as they pass through the curved portions g' of the 15 passages, and hence when the pins enter the earth they will be properly curved.

In Figs. 8 and 9 I have represented a modified form of the hollow peg and the post adapted to be located within the same. H 20 denotes the hollow peg, which is provided with ribs or looped sides h h, of which there are four, the interior of the peg being thus of the form of a cross when viewed in horizontal section. This peg H is substantially the 25 same as the peg A shown in Fig. 1. The only difference is the looped sides or ribs, of which there obviously may be any number—three, four, or more, as may be preferred. These ribs h are provided at suitable points 30 with perforations, through which the grappling pins or fingers a a are adapted to pass in the manner shown in Fig. 8. I designates a post having wings or blades I² I², of which there are four, properly shaped and constructed to adapt them to enter the interior 35 of the ribbed peg H. When the post I is placed within the peg H, the pins a, being forced out through the perforations into the earth, form a firm anchorage.

In Figs. 3 and 4 I have represented a form 40 of the device which is especially adapted for use as a surveyor's or triangulation peg. In Fig. 3, B denotes the peg, which is made hollow and similar to the hollow peg shown in Fig. 1, although it is preferably made straight 45 for a portion of its length and then conical toward the end. This peg is provided with perforations and with the grappling-pins a. It is also provided with a cap C. In Fig. 4 50 B' of the device is similar to the form B of Fig. 3, the principal difference being that it is four-sided instead of round. It is likewise provided with the grappling-pins a and with a cap or plug C'. This peg will be found to 55 be of very great value for use as a surveyor's stake or post, especially for triangulations. It will be found to possess great durability and indestructibility, there being an absolute 60 assurance of permanence and immovability, so that it cannot be transferred even a fraction of an inch from the location where it is driven by the surveyor. This will obviate a great amount of inconvenience and trouble 65 which now often occurs in the use of surveyor's pegs, thus obviating disputes and expensive lawsuits respecting division-lines and line fences and corners. After these pegs

have once been driven down into the ground and the anchors adjusted it will be found impossible to remove them except by digging 70 down and releasing the anchoring-pins. When these pegs are once fixed in place, they will remain for a long time without fear of decay or displacement. Not only can they not easily be withdrawn, but also they can- 75 not be driven farther into the ground, since the grappling-pins will serve as anchors to keep the pegs firm and immovable in any direction, either up or down, and thus they will form a firm, steady, and permanent monu- 80 ment to mark the points required by the surveyor or other person.

A particular feature of my improved anchoring device, to which I desire to direct special attention, is the fact that the grappling-pins 85 being curved and loosely adjusted through the perforations will readily adjust themselves by turning to right or left when being driven into the ground, so as to avoid any hard object with which they may come in contact.

It will furthermore be noted that in order to facilitate the driving of the straight pins into the curved holes in the solid form of the post-point above described, and illustrated in 95 Fig. 10, said pins may be heated, if desired.

Having thus described my invention, what I claim as new, and desire to secure by Letters Patent, is—

1. As an improvement in means for anchoring pegs, posts, poles, and the like, the combination, with a hollow-pointed and laterally-perforated drive peg or bar, of a suitable number of stiff independent headed metallic pins adapted to be placed by hand within the 100 said hollow drive-peg from the upper open end thereof and then forced out through the lateral perforations by means of an independent removable drive-bar and thus caused 105 to embed themselves in lateral positions in the surrounding earth, so as to firmly anchor the peg.

2. The combination, with the hollow post A, of suitable size and shape, having lateral perforations a², suitable stiff pins or fingers a, 115 said fingers being arranged independently within the hollow post and provided with heads and adapted to pass through said holes a² and fix themselves in the earth, and a fence-post, pole, or other support adapted to 120 have its lower end within the hollow of the peg A and be connected thereto by bolting or otherwise, substantially as described.

3. As an improvement in pegs for surveyors' use, a hollow or solid drive-point having 125 lateral perforations, in combination with a series of stiff independent fingers or pins adapted to pass freely through said perforations and embed themselves in the earth and a cap for the upper end of the said peg, sub- 130 stantially as described.

4. As an improvement in anchoring pegs, posts, poles, and the like, the combination of a solid pointed drive peg or bar made of suitable

material, said pointed drive-peg being provided with a suitable number of elongated passages running downward therein from the upper end of the said post, said passages being parallel to each other for a certain distance and then curving abruptly near their lower ends toward the sides of the post, and stiff independent metallic pins adapted to be inserted into the upper ends of these passages and to be driven out quickly through the bent lower parts of the passages, the pins

being bent so that they will pass out into the surrounding earth and occupy lateral positions about the post to firmly anchor and hold the same.

In testimony whereof I affix my signature in presence of two witnesses.

HENRY O. HALL.

Witnesses:

E. W. WATERS,
WM. L. BOYDEN.
